UNITED STATES PATENT OFFICE.

PHILEMON O. DICKINSON, OF NEWARK, NEW JERSEY.

DESIGN FOR A PATTERN FOR METAL STOCK.

SPECIFICATION forming part of Design No. 25,287, dated March 24, 1896.

Application filed November 14, 1895. Serial No. 568,977. Term of patent 3½ years.

To all whom it may concern:

Be it known that I, PHILEMON O. DICKINSON, a citizen of the United States, residing at Newark, county of Essex, and State of New Jersey, have invented and produced a new and original Design of a Pattern for Metal Stock, of which the following is a description, reference being had to the accompanying drawings, which illustrate the design.

10 Figure 1 of the drawings shows a front elevation or face view of a strip of metal stock bearing the design of my pattern, while Fig. 2 shows an enlarged cross-section of the same on line *a a*.

15 The general style of the design is modernized roccoco.

The design consists of a strip or ribbon of metal stock shaped in conformity with and

bearing the representation of a band A, with leaves diagonally overlying the same. At 20 each end of one section, as shown, of the pattern are located the shell terminals C, while at the middle of this section of the pattern is located the junction design or central piece D, composed of the reverse shell figures E E. 25 This section of pattern may be repeated to any extent desired.

The essential features of the design are those above indicated.

What is claimed as new is—

30 The design of a pattern for metal stock, substantially as shown and described.

PHILEMON O. DICKINSON.
